(57) **CLAIM**

The ornamental design for a bracket, as shown and described.

DESCRIPTION

FIG. 1 is a realistic perspective view of a bracket, showing my new design;
FIG. 2 is a left view thereof;
FIG. 3 is a right view thereof;
FIG. 4 is a top view thereof;
FIG. 5 is a bottom view thereof;
FIG. 6 is a front view thereof; and,
FIG. 7 is a back view thereof.

My bracket is characterized by three legs, where two orthogonal legs are threaded and are of substantially equal length and the longer third leg has a diagonally cut face in its end.
